TUBE HEATER

Godfrey W. Larson, Kansas City, Mo., assignor
to Standard Oil Company, Chicago, Ill., a cor-
poration of Indiana

Application December 30, 1933, Serial No. 704,803

12 Claims. (Cl. 122—356)

This invention relates to improvements in tube heaters, particularly tube heaters for use in the cracking and/or non-cracking distillation of petroleum oils. More particularly it relates to improvements in the arrangement of tubes, especially floor tubes within a tube heater having a radiant section and a convection section.

It is known to use one or more banks of tubes located at or near the floor of the so-called radiant section of a tube heater and it is known that this practice has many advantages, one of the most important of which is increased thermal efficiency. It is an object of my invention to increase this thermal efficiency by an improved arrangement of the floor tubes. Other objects of my invention are to reduce convective action in the radiant section, provide streamline flow and avoid local overheating. Further and more detailed objects will become apparent as the description proceeds.

I have illustrated my invention in the drawing in which:

Figure 1 is a schematic cross-sectional elevation of a tube heater embodying my invention; and

Figure 2 is a schematic cross-sectional elevation of a tube heater embodying a modified form of my invention.

Referring now more particularly to the drawing, 11 is the radiant section and 12 the convection section of a tube heater comprising side walls 13 and 14, roof 15 and floor 16. A suitable fuel such as gas, oil or powdered coal is introduced through one or preferably a series of ports 17, located near the bottom of side wall 13, by means of burners 18 controlled by valves 19. The flame from burners 18 proceeds generally upward and across radiant section 11 as indicated by lines 20 and the combustion gases pass over bridge wall 21, down through convection section 12 and out at 22 to a stack not shown.

The conventional floor tube practice in the past has been to place these tubes in a horizontal row along the conventional horizontal floor 16 (Figure 1) in radiant section 11. I find, however, that this results in poor heat pick-up or thermal efficiency since those floor tubes nearest bridge wall 21 are much further from flames 20 than those floor tubes nearest wall 13. In other words, those floor tubes nearest bridge wall 21 in the conventional arrangement have a much smaller projected area as viewed from the "hot spot" or center of heat of radiant section 11 than do those floor tubes nearest wall 13. This is particularly important in large heaters since the

"stack effect" of the hot gases in the radiant section "pulls" the flames upward resulting in a higher "hot spot" and a lower heat pick-up in the floor tubes nearest the bridge wall.

I have remedied this defect by inclining the plane of the floor tubes 23 upward towards bridge wall 21 in such a manner that the axes of the various floor tubes 23 are substantially equidistant from flames 20 or the edge thereof. In Figure 1 this is done by inclining the plane of the floor tubes, the imaginary line 24 connecting floor tubes 23 and perpendicular to them being a straight line. In Figure 2 the imaginary line 24 conforms still more closely to the shape of flame 20, the shape of line 24 in this case being substantially hyperbolic.

Floor 16 is preferably made to conform to the plane of floor tubes 23 as shown in Figure 2. This further reduces convection in radiant section 11 and avoids local overheating which otherwise results from hot gases circulating between the various floor tubes 23. The streamline flow which results from making the floor as well as the floor tubes conform to the shape of the flame also serves to protect the bridge wall tubes. Alternatively, a cheaper construction can be used consisting of a stepped construction 25 adjacent to bridge wall 21 as shown in Figure 1 or throughout the whole length of floor 16.

Under certain circumstances, as for example, when powdered coal is employed as fuel it may be advantageous to build the floor entirely in a horizontal plane or alternatively to build the floor to function as an ash pit or sump. Any of these modifications may be employed without departing from the spirit of my inventions.

It is to be understood that many different routings of oil or other fluid to be heated through a tube heater embodying my invention can suitably be used depending on the results desired to be accomplished. In the drawing the fluid to be heated enters at 26 and passes back and forth through the lower bank of convection tubes A, the cold fluid thereby picking up the last available heat from the hot combustion gases leaving the tube heater. The partially heated fluid passes out at 27 and thence to bank B composed of floor tubes 23. After passing back and forth through floor tubes 23 the fluid passes to bank C composed of tubes mounted adjacent to bridge wall 21 and wall 13. The tubes in bank C are preferably arranged so that the fluid passes around radiation space 11 first through a tube adjacent wall 21 and then through a tube adjacent wall 13. From bank C, the fluid under-

going heating passes through line 28 to roof tube bank D, shown as a double bank. After passing back and forth through the tubes of bank D the fluid passes through line 29 to upper 5 convection section bank E and thence out at 30. Conventional headers are used to connect the various tubes.

Alternatively the fluid to be heated could be passed through floor tube bank B first, thereby 10 protecting these tubes against overheating or through floor tube bank B last, thereby heating the fluid to a higher temperature. Bank C can be omitted and many other modifications are possible.

15 A similar but generally lesser advantage can be obtained by arranging the roof tubes or other tubes located above the flames to conform to the shape of the flames in the same manner as shown for the floor tubes.

20 It will be noted that the floor tubes are arranged transverse to the direction of travel of the flames. This is highly preferable to arranging them parallel to the flames since in an ordinary radiant section the tubes can thus be made to 25 conform to the shape of the flames without using curved tubes and the tubes are made readily accessible by the use of conventional headers.

While I have shown and described my invention in connection with certain specific embodiments 30 thereof, I do not mean to be limited thereby but only by the scope of the appended claims.

I claim:

1. A tube heater comprising a radiant section, a convection section, a bridge wall disposed between said radiant section and said convection section, at least one fuel burner entering said radiant section near the bottom thereof and opposite said bridge wall, the flames from said at least one burner passing generally upward and across 35 said radiant section towards the top of said bridge wall, and a row of heating tubes disposed generally below said flames and tilting upwards toward said bridge wall, the floor of said radiant section being disposed immediately below and substantially parallel to said row of heating tubes.

2. A tube heater comprising a radiant section, a convection section, a bridge wall disposed between said radiant section and said convection section, at least one fuel burner entering said radiant section near the bottom thereof and opposite said bridge wall, the flames from said at least one burner passing generally upward and across 50 said radiant section towards the top of said bridge wall, and a plurality of heating tubes arranged approximately transversely to the direction of flame travel in a bank disposed generally below said flames and tilting upwards towards said bridge wall.

3. A tube heater according to claim 2 in which 60 the floor of said radiant section is stepped upward adjacent to said bridge wall to levels immediately below the corresponding levels of said heating tubes.

4. A tube heater comprising a radiant section, a convection section, a bridge wall disposed between said radiant section and said convection section, at least one fuel burner entering said radiant section near the bottom thereof and opposite said bridge wall, the flames from said at least one burner passing generally upward and across 65 said radiant section towards the top of said bridge wall, and a plurality of heating tubes arranged approximately transversely to the direction of flame travel in a bank disposed generally below said flames and tilting upwards towards said bridge wall.

said flames and conforming generally to the shape of said flames.

5. A tube heater according to claim 4 in which the floor of said radiant section is disposed immediately below said bank of heating tubes and 5 conforms generally to the shape of said bank of heating tubes.

6. A tube heater comprising a radiant section, a convection section, a bridge wall disposed between said radiant section and said convection 10 section, at least one fuel burner entering said radiant section near the bottom thereof and opposite said bridge wall, the flames from said at least one burner passing generally upward and across said radiant section towards the top of said bridge wall, and a plurality of heating tubes arranged approximately transversely to the direction of flame travel in a bank disposed generally below said flames and lying in a substantially 15 hyperbolic surface conforming generally to the shape of said flames.

7. A tube heater comprising a radiant section, a convection section, a bridge wall disposed between said radiant section and said convection section, at least one fuel burner entering said radiant section near the bottom thereof and opposite said bridge wall, the flames from said at least one burner passing generally upward and across 25 said radiant section towards the top of said bridge wall, and a plurality of heating tubes disposed generally below said flames with their axes 30 approximately equidistant from said flames and approximately transverse to the direction of flame travel.

8. A tube heater of the open flame type comprising a burner and heating tubes disposed transversely to the direction of flame travel and arranged in a bank conforming approximately to the shape of the underside of the flame, said bank rising in a direction away from said burner 40 from a level immediately below the level of said burner to a level above the level of said burner.

9. A tube heater comprising a radiant section, a convection section, a bridge wall disposed between said radiant section and said convection section, at least one fuel burner for said radiant section near the bottom thereof and opposite said bridge wall, the gases from said at least one burner passing generally upward and across said radiant section towards the top of said bridge wall, and a row of heating tubes disposed generally below said gases and tilting upwards toward said bridge wall, the floor of said radiant section being disposed immediately below and substantially parallel to said row of heating tubes.

10. A tube heater comprising a radiant section, a convection section, a bridge wall disposed between said radiant section and said convection section, at least one fuel burner for said radiant section near the bottom thereof and opposite said bridge wall, the gases from said at least one burner passing generally upward and across said radiant section towards the top of said bridge wall, and a plurality of heating tubes arranged approximately transversely to the direction of gas travel in a bank disposed generally below said gases and tilting upwards towards said bridge wall.

11. A tube heater comprising a radiant section, a convection section, a bridge wall disposed between said radiant section and said convection section, at least one fuel burner for said radiant section near the bottom thereof and opposite said bridge wall, the gases from said at least one burner passing generally upward and 75

across said radiant section towards the top of said bridge wall, and a plurality of heating tubes disposed generally below said gases with their axes approximately equidistant from said gases 5 and approximately transverse to the direction of gas travel.

12. A tube heater comprising a radiant section, a convection section, at least one fuel burner for said radiant section near the bottom thereof, the 10 gases from said at least one burner passing gen-

erally upward and across said radiant section, and a plurality of heating tubes disposed in a row generally below said gases with their axes approximately equidistant from said gases and approximately transverse to the direction of gas 5 travel, the floor of said radiant section being disposed immediately below and substantially parallel to said row of heating tubes.
